[57] CLAIM

The ornamental design for a golf club head, substantially as shown and described.

DESCRIPTION

FIG. 1 is a front view of a golf club head.

FIG. 2 is a rear view of our new and ornamental design for a golf club head on a No. 3 iron.

FIG. 3 is a section view through line 3—3 of FIG. 2.

FIG. 4 is an end view of a golf club head having our new ornamental design on a No. 6 iron.

FIG. 5 is a rear view showing our new and ornamental design on a No. 9 iron.

FIG. 6 is a section view of FIG. 5 through line 6—6. The dominant feature of our design resides in the appearance of the rear portion of the club head.
